TAPE DISPENSER

Alwin John Stahel II, New Brighton, Minn., assignor to
The Holes-Webway Co., St. Cloud, Minn.

Filed Aug. 14, 1972, Ser. No. 280,323

Term of patent 14 years

Int. Cl. D19—02

U.S. Cl. D74—1 B

FIG. 1

FIG. 2

FIG. 3

FIG. 4

FIG. 5

FIG. 6

FIG. 1 is a perspective view showing my ornamental design for a tape dispenser;

FIG. 2 is a side elevational view of the tape dispenser, the other side of the tape dispenser being identical;

FIG. 3 is a top plan view of the tape dispenser;

FIG. 4 is a front end elevational view of the tape dispenser;

FIG. 5 is a rear end elevational view of the tape dispenser; and

FIG. 6 is a bottom plan view of the tape dispenser.

I claim:

The ornamental design for a tape dispenser, as shown and described.
